UNITED STATES PATENT OFFICE.

JOHN C. DUEBER, OF NEWPORT, KENTUCKY.

DESIGN FOR A WATCH-CASE.

SPECIFICATION forming part of Design No. 14,976, dated April 29, 1884.

Application filed December 31, 1883. Term of patent 7 years.

To all whom it may concern:

Be it known that I, JOHN C. DUEBER, a citizen of the United States, residing at Newport, in the county of Campbell and State of Kentucky, have invented a new and original Design for Watch-Cases, of which the following is a specification, reference being had therein to the accompanying drawings.

The nature of the present design is clearly and fully shown in the annexed drawings, in which—

Figure 1 is a front elevation of my ornamented watch-case, and Fig. 2 is an enlarged transverse section through the band or center of said case.

A represents the band or center of an ordinary watch-case, which band is provided with a circumferential flange or rib, B, that occupies a position midway between the front and

back of said band, as seen in Fig. 2, in which illustration the snaps have been omitted. This flange B has a series of convexities or swells, C, which swells may extend completely around the periphery of the center, or they may be interrupted at D. The front E may be of any appropriate finish, as it constitutes no part of my present design.

I claim as my invention—

The design for a watch-case herein shown and described, the same consisting of a series of swells, C, arranged around the periphery of the case.

In testimony whereof I affix my signature in presence of two witnesses.

JOHN C. DUEBER.

Witnesses:

JAMES H. LAYMAN,
SAM'L S. CARPENTER.
